CHOCOLATE CAKE

Albino Cena, Alba, Cuneo, Italy, assignor to Pietro Ferrero & C. Alba, Alba, Cuneo, Italy

Application August 6, 1958, Serial No. 52,064

Term of patent 3½ years

(Cl. D82—2)

FIG. 1

FIG. 2

Fig. 1 is a top perspective view of a chocolate cake showing my new design;

Fig. 2 is a top plan view thereof;

Fig. 3 is a side elevational view thereof; and

Fig. 4 is a sectional view taken along the lines IV-IV of Fig. 2.

I claim:

The ornamental design for a chocolate cake, substantially as shown.
